TAMPER-PROOF HINGE OR THE LIKE

Filed Sept. 6, 1945

Fig. 1

Fig. 2

Fig. II

A technical line drawing of a wedge-shaped component. The wedge tapers from a base on the left to a sharp point on the right. Four labels are present: '24' is located on the left side; '25' is on the right side, pointing to a small rectangular cutout; '26' is at the very base of the wedge; and '27' is at the top right, pointing to the top edge of the wedge.

TAMPERPROOF HINGE OR THE LIKE

Erwin L. Berkson, Chicago, Ill.

Application September 6, 1945, Serial No. 614,684

3 Claims. (Cl. 16—148)

1

This invention relates to a tamper-proof hinge or the like, the invention being specially adaptable to butt hinges such as a straight hinge, a right-angle hinge, or even to a hasp or other multi-part securing device in which the parts, more particularly, are pivoted together for so-called opening and closing movements selectively, usually when an associated lock mechanism is unlocked by authorized means.

The invention will be readily understood by reference to the following description, taken together with the accompanying drawings, of illustrative constructions embodying the invention, and in which drawings—

Figure 1 shows an adaptation of the invention to a common form of hinge for two relatively rotatable structures;

Figure 2 is a cross-section taken on the line 2—2 of Figure 1 looking in the direction of the arrows and showing in broken lines an alternative rotative position of the parts;

Figure 3 is a separated perspective view of the cover plate shown in Figures 1 and 2;

Figure 4 shows an adaptation of the invention to a slightly different form of hinge;

Figure 5 shows its adaptation to a hasp; and

Figure 6 is a separated perspective view of two different modifications of cover plate usable with the invention, the outer ends of the plates being shown broken away to save space.

Referring in detail to the illustrative constructions shown in the drawings, and turning first to Figure 1, the numerals 10 and 11 may indicate two relatively rotatable structures, one of which, say 10, might be a wall of a housing, and the other, 11, a door thereto, and arranged for such relative rotation in order to afford access to the housing, by means of swinging the door on one or more hinges, each hinge illustratively comprising a pair of similarly rotatable hinge elements 12 and 13, which, as is well known in the art, may be similar but complementary and include hinge plates, aligned hinge knuckles and hinge pin.

The hinge element 12 here shown includes hinge plate portion 14, and, angular thereto, a knuckle portion 15, the latter being in the form of two spaced apart segments 15a and 15b vertically spaced apart to receive the middle hinge knuckle portion 16 of the hinge element 13, which also includes a plate portion 17. A pintle 100 serves as a hinge pin and pivotally connects the hinge elements 12 and 13. In the hinge plate portions are one or more, in this instance three, fastener apertures 18 in each plate, by which

2

fasteners such as the screws 19 may be passed through the hinge plate portions and screwed home into the wood material for example of the relatively rotatable structures 10 and 11 respectively.

In accordance with the present invention, the hinge elements 12 and 13 in this instance are of novel construction, and element 12 will first be described, it being understood that element 13 is similar and complementary.

Struck outwardly from the plate portion 14, in the direction in which the knuckle portion 15 is angled, is a guard portion 20, this guard portion being in the form of a hood effected by making a vertical cut as at 21 in the plate portion 14 stopping short of its upper and lower margins and then extruding the metal of the plate outwardly to one side of this cut and in this instance to the side of the cut farthest away from the knuckle portion 15. This provides a guarded or hooded opening 22 facing the knuckle portion, and, aligned with this opening 22, is a slot 23 in the knuckle portion 15 through which a cover plate 24 may be slid to cover the apertures 18 and the heads of the screws 19.

The cover plate 24, as best seen from Figure 3, showing a separated perspective view thereof, is a metal plate of a width and thickness such that it may be slid snugly through the slot 23 and have its outer end 25 received under the guard 20, the main body of the cover plate covering the apertures and screw heads after the plate is so disposed. The outer end of the cover plate may be advantageously rounded or beveled as at 26 to facilitate entry into the hooded guard 20. At its other end, the cover plate carries a stop member, here shown in the form of a flange 27 thereon, thus making the cover plate of angular formation, so that its limit of movement in one direction is determined both by the hooded guard 20 and also by the flange 27, the flange preventing the end of the cover plate which carries the flange from passing through the slot 23.

Since the cover plate 24 can only be removed by retracting it from the hinge plate through the slot 23 in the opposite direction to which it is inserted, it is evident that when the hinge elements 12 and 13 are in closed position, as when the door 11 for example is closed, the cover plate 24 cannot be removed from the hinge plate 14. Consequently, the screws 19 are covered, concealed and inaccessible to anyone who might seek to tamper with the hinge for say the purpose of unauthorized entry to the housing. When, however, the door 11 is opened, presumably, under

authorized circumstances, thereby swinging the hinge elements to one relative rotative position indicated in broken lines in Figure 2 as at 28, the cover plate 24 may be removed, thereby giving access to the screws 19 and permitting removal of the hinge element 12 if desired. In removing the cover plate 24, the flange 27 conveniently serves as a handle, so to speak, by which it may be grasped for removal or insertion. It will be understood that, conversely, only when the hinge elements are in open position, as just referred to, may the cover plate 24 be inserted into position.

It will also now be understood that the hinge element 13 may have a similar hooded guard 20a but facing in the opposite direction to the guard 20 of the hinge element 12, so that the guard portions face toward each other, and the plate portion 17 may receive thereon one of the cover plates 24 through a slot 23a, similar to the slot 23 but in the knuckle portion 16 of the hinge element 13. The cover plates 24 may be similar for both hinge elements and as shown in Figure 3.

As shown in Figure 4, the invention is adaptable to a hinge in which the hinge elements are in angular relation when closed and at right-angles for example, as here shown in this figure of the drawing, the parts being generally similar except that a cover plate 29 may be here used which has its flanged inner end 30 at an obtuse angle instead of at a right-angle as in Figure 3. The obtuse angle flange 30 of the cover plate 29 thus adapts itself to the obtuse angular arrangement of the knuckle portion 31 of the hinge element of Figure 4 to the hinge plate portion 32.

As shown in Figure 5, instead of each hinge element being screwed to one of a pair of relatively movable structures, this may be true of only one of the hinge elements, in this instance 33, the other hinge element 34 being in the form of a hasp plate which is provided with the usual opening 35 through which a loop member 36 of a striking plate 37 may project, as for the reception there of a padlock, as is well known and need not be here further described. In this case, not only are the screws 19a of the plate 33 covered and concealed by the cover plate 24 and the cover plate 24 irremovable therefrom when the hasp is closed but the screws 38 of the striking plate are also inaccessible except when the hasp is opened.

As seen in Figure 6, the cover plates for each of the hinge elements of the structures of Figures 1, 2 and 3 for example, may be slightly different instead of being the same as at 24. As in Figure 6, one of the cover plates 39, say, for the hinge element 12, may have its flange 40 recessed centrally as at 41 to provide two rises 42 at each end of the flange. These rises 42 desirably require the cover plate to be wedged onto the hinge element 12 by a wedging action or contact as at 43 (Figure 2) with each of the knuckle segments 15a and 15b, the recess 41 avoiding contact of the flange with the knuckle 16 of the hinge element 13. Similarly, the cover plate 44 for the hinge element 13 has its flange 45 extended centrally as at 46 to provide a rise at this point which wedges against the knuckle portion 16 of the hinge element 13 while the flange 45 at its ends avoid the knuckle segments 15a and 15b. It will be understood that the knuckle portions are in part tubular and are aligned thus 15a, 16, and 15b, to provide aligned gudgeons for the hinge pin 100, and that if the flanges of the cover plate are not thus formed as here just described, and are formed merely as shown in Figure 3, they might

each contact all of the hinge segments 15a, 16 and 15b, and, if tight enough to be wedged into position, would be subjected to a frictional wearing action as the hinge would be opened and closed. By the formations of Figure 6, such a wedging contact is permitted while avoiding objectionable wearing or frictional contact. Thus the cover plates 39 and 44 are held in place against accidental displacement, in the event say, that the hinge elements might be arranged to open on a horizontal axis instead of a vertical axis, which latter is shown in Figures 1 and 2.

In any event, with the structures of any of Figures 1, 2, 4 or 5, and with the cover plates of either Figure 3 or Figure 6, the close proximity or butt relationship of the two relatively rotatable hinge elements adjacent their knuckle portions further prevents insertion or removal of the cover plates when the hinge is closed and therefore prevents unauthorized access to the screws holding the hinge elements to the housing or door as the case may be.

The invention is not intended to be limited to details of construction or to the specific adaptations here shown, but it is to be understood that such changes may be made as fall within the scope of the appended claims without departing therefrom.

The invention having been described, what is here claimed is:

1. In a tamper-proof hinge, the combination of a hinge element embodying a hinge plate portion and a hinge knuckle portion angular to said hinge plate portion, a fastener aperture in said hinge plate portion, a guard portion on said plate portion spaced from said knuckle portion, said guard portion being offset outwardly of the plate in the same direction as said knuckle portion is angled, a slot in said knuckle portion adjacent said plate portion, a cover plate slidably in said slot and under said guard portion, whereby to cover said aperture.

2. In a tamper-proof hinge, the combination of a pair of hinge elements hinged together and relatively rotatable to closed or open positions selectively, at least one of said elements embodying a hinge plate portion and an angular knuckle portion, a fastener aperture in said hinge plate portion, a guard portion on said plate portion spaced from said knuckle portion, said guard portion being offset outwardly of the plate portion in the same direction as said knuckle portion is angled, a slot in said knuckle portion adjacent said plate portion, a cover plate slidably in said slot and under said guard portion, whereby to cover said aperture and whereby said cover plate is removable to expose said aperture only when said hinge elements are in open position.

3. The structure of claim 2 wherein the guard portion is integral with the hinge plate portion and is struck outwardly therefrom to form a hood open at one end to receive the cover plate and closed at its other end.
